UNITED STATES PATENT OFFICE

ANTHONY HORVATH, OF WALLINGFORD, CONNECTICUT

LIFTING JACK

Application filed July 8, 1931. Serial No. 549,516.

This invention having reference to what is known in the art as a lifting jack, has for its primary object the provision of improved means for raising and lowering the load supporting part of the jack whereby to increase the efficiency of such jack, render the same more positive in action, and consequently more safe than prior jacks, in that the possibility of "slippage" is obviated or at least 10 reduced to a minimum.

While the jack contemplated by the present invention will be found especially useful for supporting one end of a scaffold platform, it is to be understood, that I desire in 15 nowise to have the device limited to this type of work, since, as will be apparent from the following description, taken in connection with the accompanying drawings, the jack is susceptible to almost any and all uses requiring a positive and efficient load raising or lowering structure.

In the drawings:

Figure 1 is a rear elevational view of the jack.

Figure 2 is a horizontal sectional view taken substantially on the line 2—2 of Figure 1.

Figure 3 is a side elevational view of the jack, the same being shown mounted on a support.

Figure 4 is a horizontal transverse sectional view taken substantially on the line 4—4 of Figure 3.

Figure 5 is a transverse horizontal section taken on the line 5—5 of Figure 1.

Figure 6 is a fragmentary detail sectional elevational view illustrative of certain details of a detent embodying the features of the present invention.

Figure 7 is a perspective view of an end portion of the rack bar.

With reference more in detail to the drawings, it will be seen that 10 designates generally what may be termed a rack bar, and which in the present instance is in the nature of a T-bar, the head flange 11 of which, at one edge is provided with a series of longitudinally spaced notches 12, which as best suited to this invention, are substantially semi-circular.

Shiftable longitudinally of the rack bar, is a carriage designated generally by the reference character 13.

As detailed in Figure 5, carriage 13 includes a body plate 14 paralleling and in sliding contact with the head flange 11 of bar 10, and provided on one face thereof with a pair of opposed guide cleats 15, the opposed faces of which are notched or grooved as at 16 for accommodating the longitudinal edge portion of the head flange 11. The cleats 15 are secured to the plates 14 by suitable fastening elements 17. Body plate 14 of the carriage at its lower edge has suitably secured thereto and extending transversely thereof a work supporting angle bar 18. (See Figures 1 to 3 inclusive).

Body plate 14 of the carriage at one edge thereof is provided with a lateral lug 19 to which is pivoted as at 20 a bell crank 21. Bell crank 21 at one end thereof is provided with a boss, in which is journaled a pin 22. Pin 22 constitutes a part of a detent structure, which also includes a disk 23 provided on one end of the pin 22. Opposed rollers 24 are journaled on eccentric pins 25 suitably secured to the disk 23, and connected by a bar 26.

Rollers 24 are engageable with the notches 12 and a study of Figure 6 will show that the rollers 24 are disposed inwardly of the periphery of disk 23, and the ends of bar 26 so that casual displacement of a roller from a notch 12 laterally with respect to the head flange 11 of the bar 10, and as may be caused by an axial shifting movement of pin 22 is guarded against.

The free end of pin 22 is equipped with a suitable crank handle 27, and from a study 90 of Figure 3, it will be seen that upon rotation of the crank handle 27, disk 23, and associated parts will rotate about the axis of the pin 22 for alternately engaging and disengaging the rollers 24 with the notches 12 95 to effect an ascent or descent of the carriage 13. Bell crank lever 21 is normally urged in one direction to thereby yieldably retain the rollers 24 in engagement with the notches 12, through the medium of a retractile spring 100.

28 connecting the free end of the bell crank with the work supporting angle bar 18.

In operation, and assuming that the device is to be used for supporting an end of a scaffold platform. In the event of such, it is apparent that at least two oppositely disposed jacks would be used each supporting an end of the scaffold platform, a portion of which is herein designated by the reference character P.

Now referring to Figure 3, the jack is first mounted, in a vertical position, on a suitable support S, and to readily adapt a jack to any type of support, there is employed an angle bar 30 one flange of which may be bolted to the support as at 31, while to the second flange of the angle bar 30, is bolted the rib flange 11a of the T rack bar 10. (See Figure 4).

Now, with the parts in the position shown in Figure 3, that is with the carriage 13 in a lowered position, and plate 18 of the carriage supporting one end of the platform P, let it be assumed that the platform P is to be raised a certain distance. Rotation of the handle 27 in a clockwise direction, thus rotating the disk 23 of the detent structure in a corresponding direction, results in the upper roller 24 remaining in engagement with its notch 12 thus causing disk 23, bar 26, and the lower roller 24 to rotate about the axis of the upper roller 24 whereupon said lower roller 24 will move out of its notch 12, to be subsequently received in that notch 12 of the rack bar directly above the notch occupied by the aforementioned upper roller, carriage 13 thus having travelled upwardly the distance between the two adjacent notches 12.

Continued repetition of the operation just described will effect a step by step raising movement of the platform P. The lower the platform the operation is obviously the reverse.

It is believed that a thorough understanding of the construction, operation and utility of an invention of this character will be apparent to those skilled in this art from a study of the foregoing description taken in connection with the accompanying drawings.

Even though I have herein shown and described the preferred embodiment of the invention, it is to be understood that I do not wish to limit myself beyond the scope of the appended claims and the requirement of the prior art.

Having thus described my invention, what I claim as new is:

1. A jack of the character described comprising in combination a bar provided with a series of longitudinally spaced notches adjacent one edge thereof, a carriage embracing said bar and shiftable longitudinally thereof, a rotatable member, means for mounting said rotatable member on the car-

riage for movement toward and away from said bar, opposed eccentric pins on said rotatable member cooperable with the notches of said bar for effecting shifting movement of the carriage, and means for rotating said rotatable member.

2. In a jack, a bar provided with a series of relatively spaced notches, a lifting device provided with means engaging the bar to constrain the lifting device to shift longitudinally of the bar, a lever pivotally mounted on the lifting device, a member rotatably mounted on the lever, and having a pair of relatively spaced pins to engage the notches of the bar, and a handle for rotating the member.

3. In a jack, a bar, a lifting device constrained to shift relative to the bar and provided with opposed guide cleats laterally engaging the bar, and means for shifting the lifting device comprising a member rotatably mounted on the lifting device, and a pair of rollers eccentrically mounted on the member and engageable with the bar, and means for rotating said member.

In testimony whereof I affix my signature.

ANTHONY HORVATH.
